UNITED STATES PATENT OFFICE.

ELMER VESHLAGE RICE, OF AZUSA, CALIFORNIA.

AUTOMATIC DAMPER.

SPECIFICATION forming part of Letters Patent No. 619,346, dated February 14, 1899.

Application filed March 19, 1898. Serial No. 674,452. (No model.)

To all whom it may concern:

Be it known that I, ELMER VESHLAGE RICE, a citizen of the United States, and a resident of Azusa, county of Los Angeles, and State of California, have invented certain new and useful Improvements in Automatic Dampers, of which the following is a specification, reference being had to the accompanying drawings, forming a part thereof, in which similar letters of reference indicate corresponding parts.

This invention relates to an improvement in automatic dampers; and the object thereof is to provide a simple inexpensive device which may be applied to any stovepipe without structural changes therein.

The invention consists, primarily, in the employment of a swinging damper and a latch therefor operated by an expansible rod, and it will be hereinafter fully described, and specifically set forth in the annexed claims.

In the accompanying drawings, Figure 1 is a side elevation of the device, partly sectional, on the line $x-x$ of Fig. 2 and showing the damper in open position; and Fig. 2 is a plan view showing the damper in closed position.

In applying my invention I employ a cross-bar A, preferably of cast-iron, adapted to extend diametrically across the stovepipe in which it is to be mounted. This cross-bar is provided at its ends with upwardly-projecting lugs a and downwardly-projecting lugs a' , which are adapted to rest in the slots B' B' on the upper edge of the lower section B of the stovepipe. The cross-bar is provided at one end with an enlarged portion a^2 , in which a threaded hole a^3 is cut. The cross-bar is also provided with a slot a^4 , communicating with the hole a^3 and extending nearly the full length of the bar. At the end opposite the enlarged portion a^2 lugs a^5 and a^6 project upwardly and downwardly from said cross-bar. A centrally-located lug a^7 affords a support for the damper C. Said cross-bar is held in position after having been placed in the slots on the upper edge of the stovepipe B by means of the upper section of the pipe b, which ships over the end of the cross-bar and over the lower section of the pipe in the usual manner.

The damper C has a slot c cut in one side thereof adapted to embrace the cross-bar

when swinging, and two lugs c' , fixed thereto, which are connected by means of the pivots c^2 to the cross-bar lug a^7 . The other side of said damper C is heavier than that containing the slot and adapted to fall into closed position automatically when released.

A latch D is pivoted to the lug a^6 by means of the pivot d . Said latch is curved toward the center of the stovepipe and is provided with a weighted end d' and a downwardly-projecting lip d^2 , adapted for engagement with the upper edge of the damper C when in open position.

An expansible rod E, of brass or other metal, of smaller diameter than that of the slot a^4 is adapted to expand longitudinally in said slot. The inner end e of said rod contacts with the latch D, and the outer end thereof is fixed to an enlarged portion e' , which threads into the enlarged head a^2 of the cross-bar A. A suitable slot e^2 in the face of said enlargement is adapted to receive a screw-driver for operating the same.

Riveted or otherwise fastened to said damper C is the stem F, which extends outwardly through a suitable hole in the side of the stovepipe and upon the outer end of which the handle G, preferably of wood, is fastened.

In the operation of the device the cross-bar carrying the damper and the latch is placed upon the edge of the lower section of the stovepipe and the upper section shipped over it. The expansible rod is then inserted and screwed into position, so that its free end contacts with the latch at e . The damper being in open position, as shown in Fig. 1, the fire is started, and as soon as the heat becomes sufficient to expand the rod E the latch is forced rearwardly to the position shown by dotted lines in Fig. 1. The upper heavier portion of the damper C will then cause the same to fall and close automatically. To re-open at any time, it is only necessary to turn the handle G, when the damper will again latch itself in position. The device may be set to operate at any predetermined degree of heat by means of the thread on the expansible rod. Should it be desired to continue the draft for a time longer than usual, the expansible rod will be screwed back out of contact with the latch, thereby allowing a certain amount of expansion before beginning

the operation of unlatching the damper. On the contrary, if it should be desired that the damper be closed in an unusually short period of time the rod would be screwed in slightly, 5 which would bring the latch to a position between that shown in full lines and that shown in dotted lines in Fig. 1. Then the action of the heat would release the damper in less time than when set as shown in Fig. 1.

10 It is obvious that structural changes may be made in the device without departing from the spirit of my invention—as, for instance, the form of the damper and latch-support sustained within the pipe and the special mode 15 of connection to the pipe and the location of the damper, latch, and thermostat relatively to each other may differ from that shown within the scope of the appended claims.

19 It will be specially noticed that the damper- 20 plate and its latch and the thermostat whereby the latch is tripped to release the damper are sustained within the draft-pipe on a support fitted therein, the only visible portions being the ordinary damper-stem and its han- 25 dle and the accessible extremity of the thermo- stat-regulator. All main parts of the de- 30 vice are thus protected within the pipe and there are no objectionable fusible parts which require renewal and the action of the devices is in all respects positive and efficient.

Having thus described my invention, what

I claim as new, and desire to secure by Letters Patent, is—

1. An automatic damper comprising a trans- 35 verse support within the draft-pipe, a radially- slotted damper-plate pivoted to said support, a latch also pivoted to the support and adapted to hold the damper open, and a thermostat guided in the support and actuating the latch to release the damper, the radial damper-slot 40 straddling the support and thermostat as the damper closes, substantially as described.

2. An automatic damper comprising a trans- 45 verse support in the draft-pipe, a radially-slot- 50 ted damper-plate pivoted to said support, a latch also pivoted to the support and adapted to hold the damper open, and a rod-thermo- stat guided in the support and having an ad- justable connection accessible from outside the pipe, and thermostat actuating the latch 55 to release the damper which in closing strad- dles at its radial slot the support and thermo- stat, substantially as described.

In testimony that I claim the foregoing as my invention I have signed my name, in pres- 55 ence of two witnesses, this 10th day of March, 1898.

ELMER VESHLAGE RICE.
